Patented Dec. 22, 1964

199,878

WHISTLE INDICATOR FOR FOOTBALL OFFICIALS AND THE LIKE

Charles T. Mulligan, 613 N. Howard St., Alexandria, Va.

Filed Feb. 4, 1964, Ser. No. 78,511

Term of patent 14 years

(Cl. D72—1)

FIGURE 1 is a perspective view of a whistle indicator for football officials and the like showing my new design.

I claim:

The ornamental design for a whistle indicator for football officials and the like, substantially as shown.
